UNITED STATES PATENT OFFICE.

JOHN O. BARDILL, OF EDWARDS, NEW YORK.

ORE-SIZING APPARATUS.

1,332,967.

Specification of Letters Patent.

Patented Mar. 9, 1920.

Application filed June 3, 1918. Serial No. 238,011.

To all whom it may concern:

Be it known that I, JOHN O. BARDILL, a citizen of the United States of America, a resident of Edwards, in the county of St.

5 Lawrence, State of New York, have invented certain new and useful Improvements in Ore-Sizing Apparatus, of which the following is a full, clear, and exact description, reference being had to the accompanying drawings, forming a part of this specification.

10 My invention relates to an apparatus for sizing ores, intended to be used in lieu of the trommels or shaking screens. The present invention has for its object the construction of an apparatus of this kind which will afford a large capacity in the treatment of crushed ores by permitting the use of a screen made up of finer wires than are used 15 in the ordinary trommel and shaking screen. This object is attained by providing in my apparatus for the distribution of a thin layer of ore on the outer surface of a cylindrical revolving screen made of fine wires, 20 and causing the finely crushed ore to pass to the interior of the screen where it is caught in a suitable receiver and conducted from the apparatus. The screen is therefore not subjected to the severe strain and wear incident to the use of the trommel and shaking screen in consequence of a mass of ore being 25 supported by and tumbled or shaken on the screen, while the fine ore is passing therethrough, and the oversize ore is being rejected at an end of the screen.

30 Figure I is a front elevation of my screening apparatus with the feed box shown in full lines as in service, and in dotted lines for access to the interior of the apparatus.

35 Fig. II is a side elevation of the apparatus.

Fig. III is a vertical transverse section.

40 In the accompanying drawings 1 designates the flanged base of my apparatus, containing a central vertical outlet opening 2 and outlet openings 3 located at opposite sides of said central opening, all of which have uses to be hereinafter mentioned. The base is surmounted by other members of a 45 housing A comprising corner pieces 4, side walls 5, a rear wall 6 and a front wall 7.

45 At the top of the housing A is a yoke or support 8 extending laterally from one of the side walls. This support serves as a 50 track upon which a feed box B is adapted

to slide so that said feed box may at one time be positioned directly over the housing, as seen in full lines, Fig. I, and at another time occupy the retracted position shown in dotted lines, Fig. I. The feed box comprises a receiving compartment b, into which the ore to be sized is delivered and from which the ore passes over a barrier 9 to enter a wide depending spout 10 forming a part of the feed box. The material entering the receiving compartment of the feed box is delivered gradually over the barrier 9 to the spout 10 and is caused to pass through the latter in a thin, even flow by providing a vertically adjustable guide 11, 55 which may be raised and lowered relative to the bottom of the spout. The feed box B serves to partially close the top of the housing A, and a removable cover 12 completes the closure. The feed box being slidably 60 mounted on the support 8 and the cover 12 being removable, access to the interior of the housing A may be quickly accomplished.

65 13 designates horizontal shafts extending from front to rear of the housing A and 70 journaled in suitable bearings secured to the front and rear housing walls. These shafts have fixed to them rollers 14 arranged in pairs, and one of the shafts is provided with an extension 13' to which power derived from any suitable source, such as an 75 electric motor mounted on the housing A, 80 may be applied.

85 15 designates deflector walls inclined inwardly from the side walls 5 to the base 1, 90 the lower ends of said walls terminating in proximity to the central outlet opening 2 in said base.

95 Within the housing A is a screen cage comprising end rings 16 joined by connecting rods 17. The rings of this cage rest upon the pairs of rollers 14 and the cage is revolved due to the application of power to one of said shafts. A screen 18 formed into the shape of a cylinder is secured to the cage 100 rings 16. This screen is composed of fine wires and therefore the wires of which it is made up do not in themselves occupy as much space as the coarse wires ordinarily used in trommels or other forms of ore sizing screens, which must necessarily be heavy to withstand the strain and wear of the load of material resting thereon while being screened or sized. Consequently, an area 105 of my screen corresponding to a similar 110

area of the heavy wire screens ordinarily used in ore sizing apparatus provides a greater number of mesh apertures, with corresponding increase in capacity of screening or sizing operation.

The ore to be screened or sized by my apparatus escapes in a gradual flow from the feed box B through its spout 10 and becomes deposited in a thin layer upon the outer surface 10 of the cylindrical screen 18, while said screen is rotated in the direction indicated by the feathered arrow, Fig. I, the ore of a size which will pass through the screen moving through its mesh in a course similar to that indicated by the downwardly pointing arrows leading to the interior of the screen, Fig. I, while the oversize material continues around the surface of the screen, as indicated by the series of arrows 15 which partially encircle said screen. The oversize material continues in the course last indicated until it escapes through the central outlet opening 2 in the base 1.

19 designates a receiving trough into which the screened material is deposited as it descends through the screen 18. This receiving trough normally occupies a position within the cylindrical screen 18, the trough extending longitudinally of the screen and being movable through an opening in the front wall 7 of the housing A. The trough is preferably of V shape in cross section and the opening in the front wall is preferably of similar shape, so that the bottom of the trough is narrower than the top, as seen in Figs. I and III. At one end of the trough 35 is a discharge opening 20 through which the screened material escapes.

21 designates an upper spray pipe extending longitudinally of the screen and its cage and 22 is a lower spray pipe parallel with said upper pipe. The upper spray pipe is provided with jet holes through which sprays of water may be directed against the cylindrical screen 18 at its outer surface at a point opposite and near the delivery of material onto the screen. The purpose of delivering sprays of water onto the screen at this point is to separate fine particles of ore 45 from the oversize pieces of ore and cause them to pass through the screen instead of being carried over with the oversize pieces. The lower spray pipe 22 is located internally of the screen and the jet holes therein 50 are so positioned as to cause water to be sprayed against the interior of the screen, whereby the mesh of the screen is freed of particles of material which lodge therein and which tend to clog the mesh to the detriment of the screening operation. The water from this lower spray pipe also assists in the flow of the oversize material to and through the outlet opening 2. Water is supplied to the upper and lower spray pipes 55 from a manifold 23 to which a conducting

hose or pipe 24 is attached, and the flow of water into said spray pipes is controlled by valves 25 and 26.

C designates a yoke attached to the receiving trough 19, the cross bar of this yoke extending transversely across the front of the machine while its arms 27 extend longitudinally along the side walls 5 of the housing A, being slidably mounted in guides 28. The yoke C permits of the receiving trough 75 being drawn outwardly from the interior of the screen 18 and supports the trough when it is withdrawn. To limit the movement of the trough and yoke when they are drawn outwardly the arms of the yoke are provided with abutments 29, of any suitable form, adapted to strike against stop lugs 30 located interiorly of the guides 29 (see full lines, Figs. I and III, and dotted lines, Fig. II). 80

When the receiving trough 19 is withdrawn from the interior of the apparatus as just explained, the spray pipes 21 and 22 move therewith and the rear ends of the trough and spray pipes become positioned at 90 the front end of the housing A, so that these members offer no interference to the removal of the screen cage with the screen thereon through the top of the housing A. Consequently, by shifting the feed box B to the position seen in dotted lines Fig. I and removing the cover 12, the screen cage may be quickly lifted out of the housing for needed repairs or any other attention it may be necessary from time to time to give it. 95

The deflector walls 15 serve to direct the oversize material that descends around the circular screens 18 so that it will pass through the outlet opening 2 at the bottom of the apparatus, as previously mentioned, 105 and they also serve to protect the shafts 13 and rollers 14. The openings 3 in the base 1 provide outlets for water and grit which may accumulate within the housing A and which would be detrimental to the bearings 110 of the apparatus if it rose to a sufficient height. The deflector walls 15 extend only between flanges of the base 1, as seen in Fig. III, and opportunity is therefore afforded for accumulated water to pass 115 around the ends of these walls to reach the discharge openings 3.

Although I have described my apparatus as an ore sizing apparatus it is obvious it may be used for screening other materials, 120 and I therefore do not limit myself to its use for any particular purpose.

I claim:

1. An apparatus of the character described comprising a hollow movably mounted 125 screen, means for delivering material to the upper and outer surface of said screen, and a receiver within said screen into which the material passing through said screen is deposited, said receiver being movably mount- 130

- ed to permit its withdrawal from said screen without disturbing the screen.
2. An apparatus of the character described comprising a support, a hollow movably mounted screen, means for delivering material to the exterior surface of said screen, a receiver movably arranged in said screen adapted to receive the material passing therethrough, and means slidably fitted to said support providing for the withdrawal of said receiver from said screen and adapted to support it when withdrawn.
3. An apparatus of the character described comprising supporting means, a hollow screen movable on said supporting means, means for delivering material to the exterior surface of said screen, a receiver adapted to receive the material passing through said screen, and supporting means for said receiver movably fitted to said supporting means, said supporting means being adapted to permit the withdrawal of said receiver from said screen to permit the removal of said screen from said supporting means.
4. An apparatus of the character described comprising supporting means, a hollow screen movable on said supporting means, means for moving said screen, means for feeding material to the outer surface of said screen, a receiver for the material to be screened movable to and from the interior of said screen, and a supporting yoke secured to said receiver and slidably fitted to said supporting means.
5. An apparatus of the character described comprising supporting means, a hollow screen movable on said supporting means, means for rotating said screen, means for feeding material to the outer surface of said screen, a receiver for the material to be screened movable to and from the interior of said screen, and a supporting yoke secured to said receiver and slidably fitted to said

supporting means, said yoke being provided with means for limiting its movement when the receiver is withdrawn from the interior of said screen.

6. An apparatus of the character described comprising supporting means, a hollow screen movable on said supporting means, means for delivering material to the exterior of said screen, a receiver movable to the interior of said screen, means for supporting said receiver permitting its withdrawal from the interior of the screen, and a spray pipe movable with said receiver through which water may be discharged against said screen when the receiver is located within the screen.

7. An apparatus of the character described comprising an open top housing, screen supporting and operating means in said housing, a screen removably seated on said operating means, a feed box slidably mounted on said housing through which material is delivered to the exterior surface of said screen, said feed box being adapted to be shifted to permit the removal of the screen through the top of said housing, and a receiver adapted to receive the material passing through said screen as it passes therethrough after delivery from said feed box.

8. An apparatus of the character described comprising an open top housing, screen operating means in said housing, a screen supported by said screen operating means, a removable cover partially closing said open top housing, a feed box slidably mounted in juxtaposition to said cover, said feed box being adapted to be retracted from its normal position to permit the removal of said screen through the top of said housing.

In testimony that I claim the foregoing I hereunto affix my signature.

JOHN O. BARDILL.
